ELECTRODE FEEDING MECHANISM FOR ARC LAMPS

Walter Kurt Krieg and Ernst Scheller, Jena, Germany, assignors to the firm Carl Zeiss, Jena, Germany

Application January 22, 1938, Serial No. 186,376
In Germany January 27, 1937

5 Claims. (Cl. 176—55)

This invention concerns electrode feeding mechanisms which impart to an electrode of an arc lamp not only a movement along but also a rotation about the axis of same.

5 An especially simple and suitable mechanism of this kind is provided by the present invention, according to which the electrode is influenced by a surrounding annular wheel rotatable about an axis intersecting the electrode axis at an acute 10 angle.

10 A mechanism of said kind is, owing to simple construction, very reliable and can be comparatively small, so that the electrode head intercepts the light arc to a comparatively small extent 15 only. To ensure as reliable an electrode displacement as possible, the interior wheel surface actuating the electrode is conveniently provided with pins or teeth of hard material.

15 In a mechanism according to the invention, 20 various speeds can be obtained by providing that the inclination of the axis of rotation of the driving wheel with respect to the electrode axis be varied. It is thus possible to control for instance the feeding speed according to different 25 electrode materials. When the inclination of the two axes relative to each other is variable by means of an electromagnet controlled by the light-arc voltage or actuated by means of a thermostat, irregularities in the electrode material 30 can be dealt with in the feed automatically.

30 The accompanying drawings illustrate a constructional example of the invention. Figure 1 shows in part-sectional view the entire mechanism; Figure 2 shows a section through line 2—2 in Figure 1; Figure 3 is a partial diagram; Figure 4 shows a section through line 4—4 in Figure 1; Figure 5 shows a section through line 5—5 in Figure 1; and Figure 6 is the diagram of a single part.

35 In this constructional example, the electrode, designated *a*, is in a holder *b*. The electrode *a* passes through a central orifice in an annular wheel *c* into which protrude the points of steel screws *c*¹, these points engaging the electrode *a*. 40 The wheel *c*, which is mounted in a ball bearing *d* and rotatable about an axis A—A, has teeth *c*² in mesh with a bevel wheel *e*. The wheel *e* is mounted in an arm *f*, which carries the ball bearing *d*. By means of a flexible shaft *e*¹ and a pair of bevel 45 wheels *e*², *e*³, the wheel *e* is connected to the armature of an electromotor *g*. A rod *h* extends into the arm *f* and is so fixed to same by a screw *h*¹ that this arm is not displaceable in the direction of the axis of this rod but can, within certain limits, effect rotations about this axis (cf.

Figure 4). The rod *h* is mounted on the holder *b* in such a manner as to be displaceable along and rotatable about its axis. By means of an arm *i* fixed to the rod *h* and carrying a square rod *i*¹ lying between two adjusting screws *f*¹ and *f*² in the arm *f*, the position of the rod *h* can be determined with respect to the arm *f* by slightly screwing back the one of the screws *f*¹ and *f*² and readjusting the other of these screws until the pin *i*¹ is in contact with both screws. A spring *j*, 10 which acts against the upper bearing of the rod *h* and against a collar *h*² fast with this rod, draws this rod downward. Against the lower side of the collar *h*² lies the one end of a fork *k* rotatable about a pin *k*¹, the other end of this fork being 15 provided with a key *k*². Below this key *k*² is a stop *k*³ resting on a support *k*⁴ on which the fork *k* is mounted. On the lower end of the rod *h* is fixed the double-armed armature *l*¹ of an electromagnet *l*. The one end of the armature *l*¹ is fast 20 with a spring *l*² endeavouring to press the other end of this armature on a stop *l*³ against the action of the electromagnet. This electromagnet is operative only when the contact of a thermostat *m* is closed, on which the luminous crater of the 25 electrode *a* is imaged when this electrode assumes a definite position.

The above-described mechanism operates as follows:

30 For the introduction of the electrode into the holder *b*, the key *k*² is to be pressed down, so that the driving wheel *c* is slightly raised against the action of the spring *j*. The hollow space in the wheel *c* thus assumes a central position with respect to the axis B—B of the electrode *a*, and the electrode can be inserted through this space. When the key *k*² is then released (as is shown in the drawings), the driving wheel *c* assumes the position eccentric to the electrode axis, and the points of the upper screws *c*¹ lie against the electrode. 35 Energizing the motor *g* causes the driving wheel *c* to rotate and the upper screws *c*¹ to carry the electrode along. On account of the inclination of the axis A—A to the electrode axis B—B (cf. Figure 3), the screw points in engagement 40 with the electrode push this electrode forward, which is due to the electrode effecting a screw motion. The desired inclination of the axis A—A relative to the axis B—B and, consequently, the desired feed of the electrode per rotation can be 45 adjusted by means of the screws *f*¹ and *f*². Unforeseen changes in the consumption of the electrode are dealt with automatically by operation of the electromagnet *l* through the agency of the thermostat *m*. 50 55

We claim:

1. In an arc lamp, a holder for an electrode, a feeding mechanism for said electrode, said feeding mechanism having an annular wheel provided with a central orifice through which the electrode passes and for feeding said electrode through said holder, said annular wheel being mounted on said holder and rotatable about an axis crossing the axis of said electrode at an acute angle and thus imparting screw motions to said electrode when said annular wheel is rotated.
2. In an arc lamp, a holder for an electrode, a feeding mechanism for said electrode, said feeding mechanism having an annular wheel provided with a central orifice through which the electrode passes, said annular wheel having pins protruding from the interior surface of same and engaging said electrode, said annular wheel being mounted on said holder and rotatable about an axis crossing the axis of said electrode at an acute angle and thus imparting screw motions to said electrode when said annular wheel is rotated.
3. In an arc lamp, a holder for an electrode, a feeding mechanism for said electrode, said feeding mechanism having an annular wheel provided with a central orifice through which the electrode passes and feeding said electrode through said holder, the axis of said annular wheel being eccentric to the axis of said electrode, a bearing body for said annular wheel being mounted on said electrode holder and rotatable about an axis intersecting the axis of rotation of said annular wheel at right angles, so that the rotation of said bearing body alters the angle of inclination at which the axis of rotation of said annular wheel crosses the axis of said electrode, and means for rotating said bearing body relatively to said electrode holder.
4. In an arc lamp, a holder for an electrode, a feeding mechanism for said electrode, said feeding mechanism having an annular wheel provided with a central orifice through which the electrode passes and feeding said electrode through said holder, the axis of said annular wheel being eccentric to the axis of said electrode, a bearing body for said annular wheel being mounted on said electrode holder and rotatable about an axis intersecting the axis of rotation of said annular wheel at right angles, so that the rotation of said bearing body alters the angle of inclination at which the axis of rotation of said annular wheel crosses the axis of said electrode, and an arc controlled means for rotating said bearing body relatively to said electrode holder.
5. In an arc lamp, a holder for an electrode, a feeding mechanism for said electrode, said feeding mechanism having an annular wheel provided with a central orifice through which the electrode passes and feeding said electrode through said holder, the axis of said annular wheel being eccentric to the axis of said electrode, a bearing body for said annular wheel being mounted on said electrode holder and rotatable about an axis intersecting the axis of rotation of said annular wheel at right angles, so that the rotation of said bearing body alters the angle of inclination at which the axis of rotation of said annular wheel crosses the axis of said electrode, an electromagnet for rotating said bearing body relatively to said electrode holder, and a thermostat positioned to receive light from the arc of the lamp and electrically connected to said electromagnet for controlling same.
